TRUSS

Filed Sept. 15, 1928

Inventor:
NORMAN B. OBBARD,
by *D. Anthony Usina*
his Attorney.

UNITED STATES PATENT OFFICE

NORMAN B. OBBARD, OF PITTSBURGH, PENNSYLVANIA

TRUSS

Application filed September 15, 1928. Serial No. 306,133.

This invention relates to trusses and, while not limited thereto, relates more particularly to light trusses suitable for use as floor joists, rafters, purlins, poles and the like, and has for one of its objects the provision of a truss of this class having improved mechanical properties over trusses of this general class.

Another object is to provide a truss which can be readily assembled from rolled material.

Another object is to provide a truss structure which is very suitable for resistance welding.

A further object is to provide a novel form of lacing bar which will support the chord members of the truss from sidewise twisting.

In the drawings:

Figure 1 is a side elevation of a truss constructed in accordance with this invention.

Figure 2 is an enlarged fragmentary side elevation of one end of the truss of Figure 1.

Figure 3 is a sectional view taken on the line III—III of Figure 2.

Figure 4 is a sectional view taken on the line IV—IV of Figure 2.

Figure 5 is a sectional view taken on the line V—V of Figure 2.

Referring more particularly to the drawings, the numerals 2 and 3 designate the upper and lower chord members, respectively, of the truss, which are generally V-shaped in cross-section and have their flanges bent outwardly adjacent their edges into a substantially horizontal plane, as at 4. The upper and lower chord members 2 and 3 are arranged with their apexes opposite or pointing toward each other and are joined by a continuous lacing bar 5 of substantially cruciform cross-section, and bent alternately up and down between said chords 2 and 3.

The lacing bar 5 is so arranged that the apexes of the chord members 2 and 3 extend into the space between two of the arms 6 of the bar 5 and the sides of the arms 6 contact with the side faces of the flanges of the chord members. The bar 5 is secured to the chord members 2 and 3 at the points of contact between the arms 6 and the flanges of the chord members, preferably by resistance welding,

as at 7, although any other means of securing the parts together may be used.

The ends of the truss are provided with diagonally arranged end supporting members 8 of substantially the same cross-section as the chord members. The members 8 are arranged with their apexes extending upwardly or in the same direction as the apexes of the lower chords and have short lengths adjacent their ends bent so as to lie in a horizontal plane parallel with the longitudinal axis of said chord members, as at 9 and 10 respectively.

The lower horizontal portion 9 of the end members 8 is adapted to fit over the lower chord member 3 and the upper horizontal portion 10 of the end members 8 are adapted to be joined to the upper chord member 2 by a short length of bar 12 of cruciform cross-section which has its opposite pair of arms 70 straddling the apexes of the portion 10 of the end member and the upper chord. The end members 8 may be secured to the chord members in any desirable manner but are preferably welded by resistance or other methods of welding.

Trusses like that above described have materially greater mechanical properties than the general form of trusses of this class, due to the novel cross-section of the chords and so lacing member.

It will be especially noted that the cruciform section used for lacing the truss has better mechanical properties than the round or square bars or rods generally used for this purpose and, due to its novel shape, it is adapted to fit over the apexes of the chords so as to provide a larger area of contact than can be obtained in any other shape of bar or rod; this contact makes an ideal condition for resistance welding.

Another advantage resulting from the use of the cruciform lacing rod is that this form of rod, when mounted as in the above described structure, serves to support the chord members against sidewise twisting strains.

While I have shown and described one specific form of my invention, it will be understood that I do not wish to be limited thereto since various modifications may be

made without departing from the scope of my invention, as defined in the appended claims.

I claim—

6 1. A metal truss composed of upper and lower chord members of generally V-shaped cross-section, said chord members being arranged with their apexes opposite each other, and a continuous lacing bar of substantially 10 cruciform cross-section bent alternately up and down between and engaging said chords, said lacing bar being so arranged that the apexes of the chord members extend into the space between two of the arms of said lacing 15 bar and the sides of the arms of the lacing bar contact with the side faces of the chords, said chords and said lacing bar being welded along their lines of contact.

2. A metal truss composed of upper and 20 lower chord members of generally V-shaped cross-section, said chord members being arranged with their apexes opposite each other and having the outer portion of their flanges bent outwardly in a substantially horizontal 25 plane, a continuous lacing bar of substantially cruciform cross-section bent alternately up and down between and engaging said chords, said lacing bar being so arranged that the apexes of the chord members extend into 30 the space between two of the arms of the lacing bar and the sides of the arms of the lacing bar contact with the side faces of the chords, and said chords and said lacing bar being welded along their lines of contact.

35 3. A metal truss composed of upper and lower chord members of generally V-shaped cross-section, said chord members being arranged with their apexes opposite each other and having the outer portion of their flanges 40 bent outwardly in a substantially horizontal plane, a continuous lacing bar of substantially cruciform cross-section bent alternately up and down between and engaging said chords, said lacing bar being so ar-

45 ranged that the apexes of the chord members extend into the space between two of the arms of the lacing bar and the sides of the arms of the lacing bar contact with the side faces of the chords, said chords and said lacing bar 50 being welded along their lines of contact, and end members extending diagonally between said chord members, said end members being of generally V-shaped cross-section and having the outer portion of their flanges bent 55 outwardly, said end members being arranged with their apexes extending in the same direction as the apex of the lower chord and having short lengths thereof adjacent each end bent into a horizontal plane parallel with

60 the longitudinal axis of said chord members, the horizontal length of the lower ends of said end members being fitted over said lower chord member and the horizontal length of the upper ends of said end members having its apex opposite the apex of 65

said top chord member and connected thereto by a short length of bar of cruciform cross-section and means for securing said chords and end members together.

4. A metal truss composed of upper and 70 lower chord members of generally V-shaped cross-section, said chord members being arranged with their apexes opposite each other, and a continuous lacing bar having its top and bottom faces grooved, said bar being bent 75 alternately up and down between and engaging said chords, said chord members having their apexes extending into the grooves in said lacing bar, and said chords and said lacing bar being welded along their lines of 80 contact.

In testimony whereof, I have hereunto signed my name.

NORMAN B. OBBARD.
